PRODUCTION OF 1,3,5-ETHYL XYLENE, META-XYLENE AND BENZENE FROM C₈ AROMATICS WITH HF-BF₃

Henry C. Thorne, Jr., Hammond, Ind., and David A. McCaulay, Chicago, Ill., assignors to Standard Oil Company, Chicago, Ill., a corporation of Indiana

Application September 26, 1952, Serial No. 311,621

10 Claims. (Cl. 260—668)

This invention relates to the conversion of C₈ aromatic components of a hydrocarbon charging stock consisting chiefly of mixed xylenes and ethyl benzene substantially entirely into 1,3,5-ethyl xylene, meta-xylene and benzene. As employed herein the expression 1,3,5-ethyl xylene is employed to denote 1,3-dimethyl 5-ethyl benzene. 15

An object of the invention is to provide such a conversion process in which by-product formation will be substantially eliminated. A further object is to provide a process in which the three desired products will be obtained in relatively pure form. A particular object is to avoid the presence of diethyl and triethyl benzenes in the ultimate product obtained. An important object is to effect the desired conversion at minimum expense and with maximum efficiency. Other objects will be apparent as the detailed description of the invention proceeds.

The charging stock should consist chiefly of C₈ aromatic components and should be as free from C₇ and C₉ aromatics as is economically feasible, the C₉ and heavier aromatics preferably constituting less than 5% of the total charge. The charge should be substantially free from olefins and the amount of paraffins should be as low as is economically feasible although about 10% or more of paraffins may be tolerated. Of the C₈ aromatics the major component should be xylene and the minor component ethyl benzene, the xylene to ethyl benzene ratio being in the range of 1.6:1 to 5:1 or more (including any recycled materials as a part of the charge). While it is preferred that meta-xylene be the major component of the xylene mixture, any mixture of ortho-, meta- and para-xylenes may be employed.

The defined charging stock is dried and complexed with about 6 to 12 mols of HF and about one mol of BF₃ based on its aromatic content in a complexing zone which is preferably at about 20 to 30° C. under a pressure of about 20 to 50 p. s. i. g. wherein the defined amounts of charging stock, HF and BF₃ are intimately mixed and contacted for a period of about 5 or 10 minutes to form a substantially homogeneous complex phase dissolved in HF which phase may contain some dissolved but uncomplexed hydrocarbons such as paraffins, which term as used herein includes naphthenes. The resulting complex stream is then pumped to a pressure of at least 200 to 300 p. s. i. g. and heated to a temperature of about 65° C., i. e. in the range of 50° to 70° C., the pressure being higher than the HF vapor pressure after the heating step so that liquid phase conditions will be insured. The complex is next passed through a reactor (in which stirring or contacting means is usually unnecessary) at said temperature and pressure wherein it is contacted in substantially homo-

2

geneous phase for a period of .4 to 4 hours, e. g. about 1/2 hour, during which time the following reactions occur:

After about one-half hour contact time in the reactor sufficient HF and BF₃ are flashed from the products to leave about 6 mols of HF and about 1 mol of BF₃ per mol of C₈ and heavier aromatic hydrocarbons contained in the product stream, most of which will be in the form of HF—BF₃ complexes. These complexes are next washed with an inert wash liquid which boils outside of the boiling range of desired products and which is preferably a light paraffinic or naphthenic hydrocarbon such as pentane to remove from the complex solution paraffinic impurities introduced with the charging stock and the benzene and toluene produced in the reactor which are not in complexed form. The removal of benzene and toluene at this point prevents undesired reactions in a later evaporating step. Pentane is distilled from the wash liquid and recycled and the hydrocarbons recovered by the pentane wash are fractionated to give substantially pure benzene and heavier hydrocarbon fractions containing toluene and C₉ paraffins.

The washed complex solution which contains dissolved pentane is next introduced into an evaporator at about atmospheric pressure to remove additional BF₃, HF and pentane, the latter being condensed, separated and returned to the wash tower if its presence in the reactor would result in formation of a separate phase. When sufficient BF₃ is liberated in the evaporator, dialkyl-benzenes such as meta-xylene (and diethyl benzene if present) are released from their complex form and dissolved in remaining complex solution. To insure the absence of diethyl benzene in the 1,3,5-ethyl xylene product, the xylenes-to-ethyl-benzene mol ratio in the charge should be relatively high, preferably greater than 3:1. When this mol ratio is substantially lower than about 3:1, the desired 1,3,5-ethyl xylene product purity may be attained by washing liberated dialkyl-benzenes from the liquid stream leaving the evaporator and recycling sufficient dialkyl benzenes thus obtained so that the effective charging stock will have a xylene:ethyl benzene ratio of about 3:1 or more. The remaining liquid from the evaporator is stripped at reduced pressure to decompose any remaining complex and to remove as much as possible of the remaining HF and BF₃ for recycle. The stripped hydrocarbons may then be neutralized and fractionated to give substantially pure meta-xylene and substantially pure 1,3,5-ethyl xylene.

The accompanying drawing, which forms a part of the specification is a schematic flow diagram of a commercial plant which can be used for processing for example, about 2,000 barrels per day of a charging stock and producing therefrom about 490 barrels per day of benzene, about

585 barrels per day of meta-xylene and about 635 barrels per day of 1,3,5-ethyl xylene.

The charging stock in this example has the following composition:

Feed composition

Component	Percent	BSD
Toluene	1.0	21
Ethyl benzene	24.8	499
P-xylene	5.3	106
M-xylene	35.5	715
O-xylene	18.3	369
C ₈ aromatics	4.3	187
Paraffins	10.8	217
	100.0	2,014

¹ 40% propyl benzenes, 40% ethyl toluene, 20% 1,3,5 trimethyl benzene.

If the charge is dry it may be introduced directly from source 10 by pump 11 into complex formation vessel 12; usually the charge contains some dissolved moisture in which case it is introduced by line 13 through dryer 14 or 14a and returned by line 15 to vessel 12. The dryers are preferably beds of calcined gamma alumina and since such dryers are well known to those skilled in the art they require no detailed description. Any conventional drying method may be employed but it is desirable that the moisture content be as low as is economically feasible.

Liquid HF is introduced into complex-forming vessel 12 by line 16 and BF₃ may be introduced thereto by line 17; in this example 6 to 12 or about 9 mols of HF are introduced and 1 mol of BF₃ is introduced per mol of aromatic hydrocarbon in the introduced charging stock. The HF, BF₃ and charging stock are vigorously stirred or otherwise agitated to insure intimate contact and effective mixing, a motor driven stirrer 18 being illustrated for this purpose although it should be understood that other stirring and/or mixing means may be employed. A contact time in vessel 12 of about 5 minutes at a temperature of about 25° C. and under a pressure in the range of about 20 to 50 p. s. i. g. is usually sufficient for effecting complex formation although somewhat longer time may be employed. The pressure in vessel 12 will be dependent upon the amount of BF₃ introduced which in turn should be approximately 1 mol, i. e. in the range of .9 to 1.2 mols per mol of BF₃ per mol of aromatic in the charge (including recycle aromatics as hereinafter described).

The substantially homogeneous liquid phase (in which some hydrocarbons may merely be dissolved rather than complexed and which may contain some undissolved paraffins) is withdrawn from complex-forming vessel 12 by line 19 and introduced by pump 20 through heat exchanger 21 to reactor 22 which is maintained at a temperature of about 65° C. (i. e. in the range of 50 to 70° C.) under a pressure greater than the vapor pressure of the HF, e. g. about 300 p. s. i. g., reactor 22 being large enough to provide a holding time of about .4 to 4 hours or in this case about 1/2 hour. In the reactor the various reactions take place as hereinabove set forth so that large amounts of benzene are formed with consequent liberation of BF₃ and HF from the complexes as introduced to the reactor. The reactor effluent is withdrawn through line 23 and a pressure reducing valve 24 into separator 25 from which sufficient HF and BF₃ is withdrawn through line 26 in amounts controlled by valve 27 to leave about 6 mols of HF and 1 mol of BF₃ per mol of C₈ and heavier aromatics remaining the complex stream which is withdrawn through line 28 to wash tower 29.

A light paraffinic hydrocarbon such as pentane is introduced in amounts of .2 to 2 volumes or more (based on introduced complex stream) by line 30 near the base of wash tower 29 for washing paraffinic hydrocarbons and uncomplexed aromatics such as benzene and toluene out of the complex. The rich wash liquid containing substantially all uncomplexed hydrocarbons is passed by line

31 and pump 32 to stripping vessel 33 which is provided with a reboiler or other heating means 34 at its base. The pentane wash liquid is thus distilled out of the uncomplexed hydrocarbons, the pentane vapors being condensed in cooler 35 and returned by line 30 to wash tower 29 which operates at ambient or room temperature.

The uncomplexed liquid from the base of stripper 33 usually contains not more than about .001% HF-BF₃ and no neutralization or purification thereof may be necessary; however, we prefer to pass this stream by pump 36 through a bauxite neutralizer system 37, such a neutralizer system being of the type commonly employed for example in HF alkylation systems. The neutralized hydrocarbons are then introduced by line 38 into benzene fractionator 39 which is provided with a suitable reboiler or heating means 40 at its base and reflux means (not shown) at its top. Any conventional fractionation system may be used and it will not be described in further detail. In this example the benzene stream removed by line 41 is approximately 490 barrels per day of benzene which is of 99.9% purity. The toluene and heavy paraffinic hydrocarbon contaminants of the initial charging stock are withdrawn from the base of fractionator 39 through line 42.

Washed complex solution leaves the base of pentane wash tower 29 through line 43 and pressure reducing valve 44 to evaporator 45 which is heated by steam coils 46. This evaporator is preferably operated at about atmospheric pressure or slightly higher. The temperature maintained in the evaporator should not be substantially higher than 100° C. The liberated HF, BF₃ and pentane is withdrawn from the top of the evaporator through line 47 and compressed by compressor 48 so that it may be returned to line 26 at the pressure maintained therein.

For increasing the purity of the final 1,3,5-ethyl xylene product in this example, sufficient BF₃ may be removed from complexes in evaporator 45 to liberate about 1,000 barrels per day of dialkyl benzenes, chiefly meta-xylene. These liberated aromatics are dissolved in the remaining complex solution and in order to free them from such solution the liquid withdrawn from evaporator 45 by line 49 may be passed through valve 50 (valve 50a being closed) to wash tower 51 wherein uncomplexed aromatics are scrubbed out of the complex solution by an inert wash liquid of the type employed in tower 29, e. g. pentane introduced through line 52 in amounts of about .2 to 2 volumes per volume of complex solution. Wash tower may be operated under the conditions of wash tower 29 in which case a cooler (not shown) will be employed between valve 50 and wash tower 51 although the washing may be effected at higher temperature. The rich wash liquid is passed through line 53 by pump 54 to stripper 55 which is provided with a heater 56 at its base so that the wash liquid may be distilled overhead and returned through cooler 57 to the base of wash tower 51. Aromatics from the base of stripper 55 are recycled by line 58 and pump 59 through cooler 60 to complex formation vessel 12, this recycled material being considered as a part of the charge aromatics in determining the amount of HF and BF₃ introduced by lines 16 and 17. Thus by controlling the amount of complex decomposition in evaporator 45, the amount of wash liquid introduced in line 52 and/or the amount of liquid passing through line 50, the amount of recycle meta-xylene can be controlled to give any desired xylene-to-ethyl-benzene mol ratio in the reactor.

Washed complex-containing liquid which leaves the base of wash tower 51 is withdrawn through line 61 and introduced together with any part of the stream withdrawn through valve 50a and line 62 through pressure release valve 63 into stripper 64. When the xylene-to-ethyl-benzene ratio in the initial charge is sufficiently high, i. e. at least about 3:1 and preferably 5:1 or more, valve 50 may be closed and the entire liquid stream from

evaporator 45 may be introduced through open valve 50a, line 62 and pressure reducing valve 63 into stripper 64. Stripper 64 is provided with a reboiler or other heating means 65 and it is operated at as low a pressure as is economically feasible, usually in the range of 10 to 200 mm. absolute and with a bottom temperature in the range of 100 to 150° C. The HF and BF₃ vapors from stripper 64 are passed through line 66 by compressor 67 to line 47.

The hydrocarbons released from HF and BF₃ in stripper 64 are withdrawn through line 68 by pump 69 which introduces them into neutralization system 70. The stream withdrawn through line 68 may contain as much as .01% HF-BF₃ and hence may require caustic scrubbing or more drastic neutralization treatment than is given to the stream withdrawn from pentane stripper 33. The neutralization may be effected by well known means and hence requires no detailed description.

The neutralized stream is then introduced by line 71 to meta-xylene fractionator 72 which is provided with a reboiler or heating means 73 at its base. Tower 72 is a schematic representation of a fractionation system that may require three towers in actual practice, but since no invention is involved in the fractionation system it will not be described in detail. Meta-xylene of at least about 99% purity is withdrawn through line 74 in amounts of about 584 barrels per day. A lighter mesitylene stream is withdrawn through line 75 in relatively small amount. The desired 1,3,5-ethyl xylene of high purity is withdrawn through line 76 in amounts of about 635 barrels per day. Any 1,3,5-propyl xylene and other bottoms materials are withdrawn through line 77. Thus the three desired products, benzene, meta-xylene and 1,3,5-ethyl xylene, each in a state of high purity, are recovered in a total amount of about 95% or more of the total C₈ aromatics in the original charge.

The HF and BF₃ from lines 26 and 47 is partially condensed in cooler 78 and separated into gaseous and liquid components respectively in separator 79. The liquid component separates into an HF phase and a pentane phase. The HF phase is passed by pump 80 through cooler 81 and line 16 to complex-forming vessel 12. The gaseous component, chiefly BF₃, is passed by compressor 82 through cooler 83 and line 17 to complex-forming vessel 12. Make up HF is introduced as required from source 84 and make up BF₃ is similarly supplied from source 85. The separated pentane phase is returned by line 86 and pump 87 to wash tower 29 or 51 when its presence in vessel 12 and reactor 22 would result in formation of substantial amounts of a separate paraffinic hydrocarbon phase. When the charge is sufficiently free from paraffins, the pentane may be recycled with HF to vessel 12, but it is important to have a substantially homogeneous phase in reactor 22 and hence the paraffins and/or naphthenes introduced thereto must be held within close limits, i. e. must not greatly exceed about 10%. For a completely homogeneous phase, the amount of paraffins present should be less than 1%.

As another example of the invention the hereinabove defined process may be applied to a charging stock containing on a volume basis 1.3% toluene, 31.2% ethyl benzene, 6.5% para-xylene, 44.4% meta-xylene, 5.6% ortho-xylene and 11% paraffins with substantially no C₉ aromatics; from about 1,600 barrels per day of such a charging stock, about 500 barrels per day of substantially pure benzene, about 400 barrels per day of meta-xylene and about 500 barrels per day of 1,3,5-ethyl xylene may be obtained.

By employing the procedural steps, proportions and conditions hereinabove defined a 1,3,5-ethyl xylene product can be obtained which is substantially free from diethyl benzene. If the charge composition, HF-BF₃ proportions and/or operating conditions are modified to such an extent that the 1,3,5-ethyl xylene product is contami-

nated by undue amounts of diethyl benzene an alternative procedure may be utilized to prevent such contamination. As HF and BF₃ are removed from complex in evaporator 45 more and more hydrocarbons are liberated from complex. The 1,3,5-ethyl xylene complex is very much more stable than the meta-xylene complex or the diethyl benzene complex (the latter two being of substantially equal stability). Thus in evaporator 45 sufficient HF and BF₃ may be removed to liberate all meta-xylene and ethyl benzene and to leave the 1,3,5-ethyl xylene in complex form. In such a case the total liquid leaving evaporator 45 may be washed with a light paraffinic hydrocarbon in wash tower 51 and additional HF may be introduced to insure that the 1,3,5-ethyl xylene complex remains in solution in the HF phase. In this case the washed complex can then be introduced into HF-BF₃ stripper 64 for releasing the 1,3,5-ethyl xylene and if all of the meta-xylene has previously been removed the 1,3,5-ethyl xylene may simply be distilled from heavier hydrocarbons. After removing the wash liquid from the liberated meta-xylene and diethyl benzene the net product meta-xylene may be distilled from the diethyl benzene and the latter, without neutralization or purification but with the amount of meta-xylene desired for recycle, may be recycled to complex-forming vessel 12. The recycled diethyl benzene is thus ultimately converted entirely to benzene and 1,3,5-ethyl xylene. In this case the meta-xylene which is separated from diethyl benzene by distillation may require neutralization and/or treating to remove residual amounts of HF and BF₃ but it should require no further fractionation or purification.

For increasing 1,3,5-ethyl xylene production, ethylene can be added to line 19 or directly to the base of reactor 22 for alkylating meta-xylene to 1,3,5-ethyl xylene in addition to reactions previously set forth. The ethylene is added after the complexing step in vessel 18 because with HF alone, fully alkylated tetraethyl xylene would be formed whereas the introduction of ethylene into the complex solution in or entering reactor 22 results almost exclusively in 1,3,5-ethyl xylene. The amount of ethylene so introduced must be so limited that the mol percent of xylenes in the reactor effluent will exceed the mol percent of ethyl xylene, the ethylene introduced to the reactor corresponding on a mol basis to increasing the amount of ethyl benzene in the original charge.

From the foregoing description of particular examples it will be apparent that the objects of the invention have been attained. It should be understood, however, that the invention is not limited to the details recited in these examples since alternative procedural steps and operating conditions will be apparent from the above description to those skilled in the art.

We claim:

1. A process for converting the C₈ aromatic components of a hydrocarbon charging stock consisting chiefly of mixed xylenes and ethyl benzene substantially entirely into benzene, meta-xylene and 1-, 3-dimethyl, 5-ethyl benzene which process comprises complexing the aromatic components of said charging stock in substantially dry state with at least about 6 mols of HF and 1 mol of BF₃ per mol of total aromatic hydrocarbon in the charge in a complexing zone, increasing the pressure and temperature on the complexes thus formed and holding complexes at a temperature in the range of about 50° C. to about 70° C. under a pressure of at least 200 p. s. i. g. and high enough to insure liquid phase conditions long enough to convert said C₈ aromatic hydrocarbons substantially entirely to benzene, meta-xylene and 1-, 3-dimethyl, 5-ethyl benzene, removing sufficient HF and BF₃ liberated from complexes in the reaction step to leave about 6 mols of HF and about 1 mol of BF₃ per mol of C₈ and heavier aromatic hydrocarbons contained in the product stream, thereafter removing uncomplexed hydrocarbons from the complexes by washing said complexes countercurrently with a saturated hydrocarbon, evaporating HF and

BF_3 from the remaining complexes at approximately atmospheric pressure in an evaporating zone, withdrawing liquid from the evaporating zone to a decomposing zone, decomposing remaining complexes in said last named zone at reduced pressure, compressing HF and BF_3 from the evaporating zone and the decomposing zone and combining the compressed vapors with HF- BF_3 initially released from complexes leaving the reaction step, cooling the combined stream, pumping the liquid component of the cooled stream through a further cooler to the complexing zone, compressing a gasiform component of the cooled stream and passing the compressed material through a further cooler to the complexing zone, removing any residual HF and BF_3 from the liquid stream from the decomposing zone and fractionating said stream to obtain substantially pure 1-, 3-dimethyl, 5-ethyl benzene.

2. The process of claim 1 which includes the additional steps of washing at least a part of the liquid stream from the evaporating zone with a saturated hydrocarbon for separating liberated hydrocarbons from undecomposed complex in said stream, and recycling at least a part of said liberated hydrocarbons to said complexing zone.

3. The process of claim 1 which includes the step of separating wash liquid from the liquid component of the cooled stream and returning said separated wash liquid to said washing zone.

4. The process of claim 1 wherein the uncomplexed hydrocarbons removed by washing include benzene and other uncomplexed hydrocarbons and which includes the step of recovering substantially pure benzene from other hydrocarbons thus removed from complex.

5. The process of claim 1 wherein the saturated hydrocarbon is pentane.

6. The method of producing benzene, meta-xylene and 1,3-dimethyl, 5-ethyl benzene which comprises complexing the aromatic components of a charging stock consisting chiefly of mixed xylenes and ethyl benzene in the ratio of about 1.6:1 to 5:1 and less than 10 percent of paraffinic and naphthenic hydrocarbons in the substantial absence of water with about 6 to 12 mols of HF and 1 mol of BF_3 per mol of total aromatic hydrocarbon in the charge in a complexing zone at a temperature of about 20° to 30° C. under a pressure of about 20 to about 50 p. s. i. g., pumping the resulting substantially homogeneous complex to a pressure of at least about 200 p. s. i. g. and heating it to a temperature in the range of about 50° C. to about 70° C., said pressure being sufficient to maintain the HF in liquid phase at said temperature, maintaining the complex at said temperature and pressure for a period of about .4 to 4 hours, then reducing the pressure on reaction products to remove liberated HF and BF_3 and to leave about 6 mols of HF and about 1 mol of BF_3 per mol of C₈ and heavier aromatics in the product liquid, thereafter scrubbing the product liquid with a wash liquid to remove substantially all aromatic hydrocarbons which are not complexed with HF and BF_3 , reducing the pressure on the scrubbed complex to approximately atmospheric pressure and removing additional HF and BF_3 from the product liquid to effect liberation of at least a portion of complexed meta-xylene, thereafter stripping product liquid at a pressure in the range of 10 to 200 mm. at a temperature in the range of 100° C. to 150° C. to decompose remaining complex and liberate HF and BF_3 to the complexing step and fractionating the product liquid to recover substantially pure 1,3-dimethyl, 5-ethyl benzene.

7. The method of claim 6 which includes the step of recycling liberated meta-xylene to the complexing zone in amount sufficient to maintain a xylene to ethyl benzene ratio in said zone of at least about 3:1.

8. A process for converting the C₈ aromatic components of a hydrocarbon charging stock consisting chiefly of mixed xylenes and ethyl benzene in the ratio of about 1.6:1 to 5:1 substantially entirely into benzene, meta-xylene and 1,3-dimethyl, 5-ethyl benzene, which process comprises complexing the aromatic components of said

charging stock in the absence of appreciable amounts of water with 6 to 12 mols of HF and 1 mol of BF_3 per mol of total aromatic hydrocarbon in the charge in a complexing zone maintained at a temperature of about 20° C. to 30° C. and a pressure of approximately 20 to 50 p. s. i. g., effecting substantially homogeneous phase conversion by reacting the resulting complex solution at a temperature in the range of 50° C. to 70° C. for a period of about .4 to 4 hours under a pressure greater than the vapor pressure of hydrogen fluoride at said temperature, removing from the effluent product stream HF and BF_3 liberated in the reaction zone to leave about 6 mols of HF and about 1 mol of BF_3 per mol of C₈ and heavier aromatics in the product liquid, then washing in a wash zone the product liquid with about .2 to 2 volumes of saturated low boiling hydrocarbon to remove substantially all hydrocarbons which are not complexed with HF and BF_3 , distilling said saturated low boiling hydrocarbon from the rich solution thus obtained and recycling said saturated low boiling hydrocarbon to the washing step, fractionating the removed uncomplexed hydrocarbons to obtain substantially pure benzene, introducing washed complex into an evaporator zone at approximately atmospheric pressure, heating said complex in the evaporator zone to liberate dissolved pentane and further amounts of HF and BF_3 , introducing liquid from the first evaporating zone to a second wash zone, washing liberated aromatics from said last named liquid in the second wash zone, passing washed liquid from the second wash zone to a decomposing zone operated at a pressure in the range of 10 mm. to 200 mm. absolute with a bottom temperature in the range of 100° C. to 150° C. to decompose all remaining complex and liberate HF and BF_3 therefrom, compressing HF and BF_3 from the decomposing zone and from the evaporator zone to the pressure of HF and BF_3 initially released from reactor effluent and combining the streams of liberated HF and BF_3 , cooling the combined streams and separating them into a liquid and gaseous component, pumping at least a part of the liquid component through a cooler to the complexing zone, compressing the gaseous component and introducing it through a cooler to the complexing zone, removing any residual HF and BF_3 from hydrocarbons released in the decomposing zone and fractionating said hydrocarbons to recover substantially pure meta-xylene and substantially pure 1,3-dimethyl, 5-ethyl benzene respectively.

9. The process of claim 8 which includes the steps of separating the liquid component of the cooled combined streams of HF and BF_3 together with saturated low boiling hydrocarbon contained therein to obtain a liquid saturated low boiling hydrocarbon stream and returning said last named stream to said wash zone.

10. A process for making 1,3-dimethyl, 5-ethyl benzene from the C₈ aromatic components of a hydrocarbon charging stock consisting chiefly of mixed xylenes and ethyl benzene together with additional ethylene which process comprises complexing the aromatic components of said charging stock with 6 to 12 mols of HF and about 1 mol of BF_3 per mol of total aromatic hydrocarbon in the charge in a complexing zone, effecting homogeneous phase conversion by reacting the resulting complex at a temperature in the range of about 50° C. to 70° C. for a period of about .4 to 4 hours under a pressure greater than the vapor pressure of hydrogen fluoride at said temperature, introducing said additional ethylene into the homogeneous phase after said complexing step in such amounts that the mol percent of complexed 1,3,5-ethyl xylene formed in the reactor does not exceed the mol percent of xylenes therein, reducing the pressure on the reaction products to remove liberated BF_3 and some HF and to leave about 6 mols of HF and about 1 mol of BF_3 per mol of C₈ and heavier aromatics in the product liquid, thereafter scrubbing the product liquid with a wash liquid to remove substantially all hydrocarbons which are not complexed with HF and BF_3 , reducing the pressure on the scrubbed complex solution, heating said complex solu-

tion at said reduced pressure in an evaporator zone to liberate further amounts of HF and BF₃, stripping liquid from the evaporator zone at reduced pressure and at a temperature in the range of about 100° C. to 150° C. to decompose any remaining complex and liberate further amounts of HF and BF₃, recycling liberated HF and BF₃ to the complexing step, removing any residual HF and BF₃ from hydrocarbons withdrawn from the stripping zone and fractionating said hydrocarbons to recover substantially pure 1,3-dimethyl, 5-ethyl benzene.
